UNITED STATES PATENT OFFICE

FREDERICK L. SCHLEICHER, OF ST. LOUIS, MISSOURI, ASSIGNOR TO THE SCHLEICHER CORPORATION, OF WILMINGTON, DELAWARE, A CORPORATION OF DELAWARE

MACHINE FOR DESCALING BOILERS

Application filed December 27, 1927. Serial No. 242,551.

My invention relates to machines that produce by abrasion a finely divided metallic material that will remain in suspension in the feed water being pumped into a boiler, and, has for its object to improve my machine for the same purpose filed in the United States Patent Office on the 4th day of October, 1926, and bearing Serial Number 139,542, first, by providing an abradant rotor which is suspended in the water chamber of the casing of the machine, and, second by providing abrasive brushes for contact with the rotor having connections of the same material for pivotal connection with supporting pins, so that the body of each abrasive brush can be completely worn down and automatically severed from its connections by abrasion, thus leaving nothing but the connections to be removed when applying new brushes to the machine.

A further object of the invention is the provision of a machine, which possesses advantages in points of simplicity and efficiency, and, at the same time proves itself comparatively inexpensive in cost of manufacture.

With the above and other objects in view, the invention consists in the novel features of construction, arrangement and combination of parts hereinafter more fully described and finally pointed out in the claims hereto appended.

Referring to the accompanying drawings forming a part of this specification, wherein like characters of reference denote similar parts throughout the several views:

Fig. 1, is a top plan view of the machine with the cover plate and parts carried thereby removed from the casing and with a part of the casing shown in sectional elevation.

Fig. 2, is a vertical sectional view of the casing, with the cover plate and parts carried thereby removed and showing the abrading rotor and the brushes within the casing in side elevation.

Fig. 3, is a vertical sectional elevation of the machine.

Fig. 4, is a detail in vertical sectional elevation of the abrading rotor, a part of the cover plate and the bevel gear.

Fig. 5, is a top plan view of the machine. In carrying out the aim of my present invention, I employ a suitable casing 1 having an open top which is closed by means of a suitable closure plate 2 to provide a water and abrading chamber 3. The cover plate 2 is secured to the wall of the casing by means of suitable fastening devices 4. The side wall of casing 1 is provided with a pair of opposed openings 5 and 6 which communicate with the water chamber 3. One of said openings is a water inlet opening and the other opening is a water outlet opening. The casing 1 is connected in the water feed line to the boiler, preferably in advance of the suction pump, not shown.

As clearly shown in Fig. 3 and in detail in Fig. 4, a sleeve member 7 of suitable bearing material having a reduced screw threaded upper end to provide a nipple 8 and shoulder 9 depends from the cover plate 2 centrally thereof. The sleeve member 7 is connected to the cover plate 2 by means of the nipple 8 which is received by a central screw threaded opening 10 in the cover plate 2 and with the shoulder 9 of the sleeve member engaging the lower face of the cover plate 2 to limit upward movement of the sleeve member relative to the cover plate. The sleeve 7 is provided with a bore of two diameters designated 11 and 12 so as to provide an upper bearing section 13 and a packing chamber 14.

A driven shaft 15 is mounted in the bearing section 13 of sleeve 7 and passes downwardly to the lower end of the packing chamber 14. The packing chamber 14 is adapted to receive a suitable packing material 16 backed by a bearing sleeve 17 which also acts as a packing gland and which is held in the desired contact with the packing by means of a plug 18 having screw threaded engagement with the lower end of the bearing sleeve 7 which permits of tightening the packing 16 when necessary. The plug 18 is provided in its outer face with a slot 19 for receiving a convenient tool for turning the screw plug 18. The upper end of the driven shaft 15 is reduced in diameter to provide a shoulder 20 and the reduced upper extension 21 which extends upwardly beyond the upper face of the

sleeve 7 to receive the hub section 22 of a bevel gear 23. The gear 23 is connected to the extension 21 of the shaft 15 by means of a suitable key 24 and locked thereto by means of a nut 25 carried by the upper end of the reduced upper extension 21 of the shaft 15 and which nut engages the upper face of the bevel gear 23. A suitable ball bearing 26 is seated in a recess 27 in the upper face of the cover plate 2. The hub 22 of the gear 23 passes through the ball bearing and the lower face 27 of the gear 23 engages the upper face of the ball bearing 26, as clearly shown in Fig. 4. The bevel gear 23 and the ball bearing 26 are both disposed within a housing 28 forming a part of the cover plate 2 and which housing is provided with the chamber 29 for receiving a lubricant for the gear and the ball bearing, as clearly shown in Fig. 3. The housing is provided with a removable cover plate 30 for gaining access to the parts within the chamber 29 and for filling the chamber with lubricant.

The lower end of the driven shaft 15 is reduced in diameter to provide a shoulder 31 and the reduced lower extension 32 which extends downwardly beyond the lower face of the sleeve member 7 to receive the hub section 33 of a head member 34. The head member 34 is connected to the extension 32 of the shaft 15 by means of a suitable key 35 and locked thereto by means of a nut 36 carried by the lower end of the lower reduced extension 32 of the shaft 15 and which nut engages the lower face of the head member 34.

Surrounding the sleeve member 7 is a cylindrical member 37 having a reduced bore 38 at its upper end to receive a suitable oilless bearing 39 which is disposed between the sleeve member 7 and the cylindrical member 37. The cylindrical member 37 is provided with an upper laterally directed flange 40 and a lower laterally directed flange 41, both of which are of the same diameter and to which is applied a suitable abradant cylinder 42. The abradant member 42 is secured to the flanges 40 and 41 by shrinking the same thereon so that it will be held thereon against displacement. The abradant cylinder 42 extends downwardly a little beyond the lower flange 41 so as to provide a recess 43 to receive head member 34, the lower face of which lies flush with the lower face of the abradant cylinder 42. The cylindrical member 37 is secured to the head member 34 by means of suitable fastening devices, such for instance as screws 44 which have connection with the lower flange 41, so that when the shaft 15 is rotated the motion is imparted to the cylindrical member 37 and the abradant cylinder 42 which is carried by the cylindrical member 37. A pinion 45 carried at the inner end of a shaft 46 which has a flexible connection 47 with the drive shaft 48 of a suitable electric motor 49, which motor is shown for con-

venience in conventional form and as carried by a supporting shelf 50 forming a part of the cover plate 2, so that when the cover plate 2 is removed from the casing 1, the motor need not be disconnected from its supporting shelf 70 50. The cover plate 2 is provided upon the side opposite the shelf 50 with a suitable handle extension 51 so that the cover 2 may be lifted from the casing 1 by means of the shelf 50 and the handle extension 51. 75

A plurality of vertically disposed studs 52 are suitably connected at their lower ends to bosses 53 on the lower wall of the casing 1 and the studs are arranged in equal spaced relation within the chamber 3 of the casing 1 80 and surround the rotatable abradant cylinder 42. The spaced apart ears 54 of cast metallic brushes 55 that are to be abraded by the abradant cylinder 42 to form a suspended material to be fed to the feed water entering a boiler are journaled on the studs 52. There is one brush to each stud and the brushes 55 and their spaced ears 54 are made of the same material so that the brushes 55 can be completely worn down by abrasion leaving nothing but the ears 54 which are severed by abrasion from the brushes. The brushes 55 are normally held in engagement with the vertically disposed rotary abradant cylinder 42 by means of suitable springs 56 coiled around the studs 52 each having an end 57 bearing against the upper of the two ears 54 of each brush 55 and clamping over the same, and the other end 58 bearing against a respective pin 59. The pins 59 are suitably connected to the bosses 53 on the lower wall of the casing 1 and are disposed adjacent each stud 52, as clearly shown in Fig. 1. 90

There can be no jamming of the abradable brushes 55 with the rotatable abradant cylinder 42, or in the water chamber 3 of the casing 1, as the brushes 55 are pivotally supported in equal spaced relation to each other and are not free to any other movement than pivotal movement as they are being abraded. The abrading action on the brushes 55 is continuous as long as there is any body left to be abraded as the abradant cylinder is rotated continuously by means of the electric motor. 105

The many advantages of the herein described invention will readily suggest themselves to those skilled in the art to which it appertains.

From the foregoing description, it is evident that a simple device for this purpose has been disclosed, but it is to be understood that I do not desire to restrict, or limit myself to the very details of the construction shown and described, which is merely illustrative, it being obvious that changes, not involving the exercise of invention may be made without conflicting or departing from the spirit of the invention within the scope of the appended claims. 115 120 125 130

What I claim is:

1. In a device for abrading material to be supplied to feed water to a boiler in a suspended state, a casing having opposed water inlet and outlet openings, a rotatable abradant cylinder suspended from the top wall of the casing and free of contact with the opposite wall of the casing, a plurality of horizontally disposed pivotally supported brushes of descaling material to be abraded by contacting with the side wall of the vertically disposed cylinder and resilient means for progressively feeding the brushes to the wall of the cylinder. 5
2. In a device of the class described, a casing having a water chamber provided with an inlet opening and an outlet opening, a removable cover plate for the casing, a bearing sleeve fixed to and suspended from said cover plate, a shaft passing through said sleeve, a packing surrounding said shaft and disposed within said sleeve, a movable combined bearing sleeve and packing gland within said sleeve and surrounding said shaft, a screw threaded plug carried at the lower end of the bearing sleeve for contact with said combined sleeve bearing and packing gland, a flanged cylindrical member surrounding said bearing sleeve, an oilless bearing disposed between said cylindrical member and said bearing sleeve, an abradant cylinder carried by said flanged cylindrical member, a head member secured to the lower end of said shaft, means for securing said cylindrical member to said head member, a bevel gear secured to the upper end of said shaft, a ball bearing disposed between said bevel gear and the cover plate, a housing forming a part of the cover plate for housing said gear and ball bearing and for containing lubricant, a driving shaft extending into said housing and a pinion carried by said driving shaft meshing with said bevel gear for imparting rotary movement to the abradant cylinder. 10
3. In a device of the class described, a casing having a water chamber provided with an inlet and an outlet, a rotatable abradant cylinder, brushes of descaling material, spaced ears directed from said brushes of the same material as the brushes, studs carried by the casing upon which the ears of said brushes are journaled, a pin adjacent each stud, coiled springs mounted on said studs each having one end bearing against its respective pin and the other end thereof bearing against one of the ears of each brush to normally and frictionally contact the brushes with the rotary abradant cylinder. 15
4. An abradant rotor for machines of the class described, a bearing sleeve fixed to and suspended from a support, a shaft passing through said sleeve, a packing surrounding said shaft and disposed within said sleeve, a movable combined bearing sleeve and pack- 20
- ing gland within said sleeve and surrounding said shaft, a screw threaded plug carried at the lower end of the bearing sleeve for contact with said combined sleeve bearing and packing gland, a flanged cylindrical member surrounding said bearing sleeve, an oilless bearing disposed between said cylindrical member and said bearing sleeve, an abradant cylinder carried by said flanged cylindrical member, a head member secured to the lower end of said shaft and means for securing said cylindrical member to said head member. 25
5. A brush for abrading machines of the class described comprising a body of descaling material to be abraded and a pair of spaced ears directed from said body adapted to be journaled upon supports for swinging movement, said ears being of the same material as the body so that the entire body can be severed from the ears by abrasion. 30
6. In a device of the class described, in combination a casing having a water inlet and a water outlet in diametrically opposite relation, a removable cover for said casing, a vertically disposed abradant cylinder suspended from the cover and removable from within the casing with the cover, a plurality of horizontally disposed abradable brushes of boiler descaling material pivotally supported for progressive arcuate movement into abrading contact with the outer surface of the abradant cylinder, said abradable brushes being arranged in opposed relation and diagonally arranged relative to the pivot points of the abradable brushes and means supported by the cover and removable therewith for rotating the aforesaid abradant cylinder. 35
7. In a device for abrading material to be supplied to feed water to a boiler in a suspended state, a casing, a cover for said casing, a rotatable abradant cylinder suspended in a vertical position within the casing from the cover of the casing and free of contact with the bottom wall of the casing, horizontally disposed pivotally supported brushes of boiler descaling material adapted for abrading contact with the side wall of the vertically suspended abradant cylinder, resilient means for progressively feeding the brushes to the side wall of the abradant cylinder, the said brushes each adapted to be completely submerged in water passing through the casing as they are abraded. 40
- In testimony whereof, I have hereunto affixed my signature. 45
